UNITED STATES PATENT OFFICE.

WILLIAM O. CUTTER, OF EAST WAREHAM, MASSACHUSETTS.

TORPEDO-BOAT.

1,355,894.

Specification of Letters Patent. Patented Oct. 19, 1920.

Application filed March 25, 1918. Serial No. 224,569.

To all whom it may concern:

Be it known that I, WILLIAM O. CUTTER, a citizen of the United States, residing at East Wareham, in the county of Plymouth and State of Massachusetts, have invented 5 new and useful Improvements in Torpedo-Boats, of which the following is a specification.

This invention relates to improvements in 10 torpedo boats and the object thereof is to provide a small, compact boat capable of being operated at a high rate of speed by one man, if necessary, to convey and discharge a torpedo at a certain object, said 15 boat having a substantially invulnerable compartment within which the operator thereof is stationed and capable of floating independently of the other sections of said boat, and even though practically all other 20 portions of the boat may have been shot away or destroyed, the operator's compartment will remain substantially intact and may be quickly disconnected from what is left of the other sections and remain afloat 25 until the operator thereof has been rescued.

Another object of the invention is in the provision of means extending to all sections 30 of the boat from the operator's compartment for the purpose of operating the various devices carried by said sections, such as the torpedo instrumentalities and the steering and propelling instrumentalities, said means being so formed that when the operator's compartment is disconnected from the other portions of the boat, said connecting 35 means will be automatically disconnected, thereby freeing itself from any of the injured portions of the boat.

Another object of the invention is to provide 40 a boat which may be constructed very cheaply so that in case it is destroyed by enemy gun fire or otherwise, its loss will not be of very great importance. Furthermore, 45 the boat is capable of floating with only a portion of the same protruding from the water, so that it will be practically unobserved as it approaches its object.

The invention consists in the combination 50 and arrangement of parts set forth in the following specification and particularly pointed out in the claims.

Referring to the drawings:

Figure 1 is a plan view of a boat embody-

ing my invention, portions thereof being 55 broken away to save space in the drawings.

Fig. 2 is a vertical longitudinal section through the forward portion of the boat.

Fig. 3 is an enlarged side elevation of the 60 prow, illustrating the opening through which the torpedoes are discharged.

Fig. 4 is a transverse section taken on the line 4—4 of Fig. 3.

Fig. 5 is a longitudinal vertical section 65 through the stern section of the boat.

Fig. 6 is a detail vertical section through the central portion of the boat, illustrating the manner in which the operating section and forward and stern sections are joined 70 together.

Fig. 7 is a detail section illustrating the means for locking the forward and stern sections together.

Like numerals refer to like parts through- 75 out the several views of the drawings.

In the drawings, 1 is the forward section, 2 the stern section and 3 the operating section of a boat. The forward and stern sections of the boat are placed end to end and 80 in abutting relation, preferably along the line indicated at 4, Fig. 1. The forward section 1 of said boat is provided with a bulkhead 5 disposed at a distance from the edge 4 and the section 2 is provided with 85 a bulkhead 6 disposed at a distance from the abutting end 4 thereof, so that when the two sections are secured together a chamber 7 will be formed, partly in one section and partly in the other, and in this chamber the 90 operator section 3 is adapted to be inclosed.

The operating section 3 is preferably made spherical in shape so as to more readily resist the shot or shell which may be fired at the same and thereby provide greater 95 protection for the operator of the boat. This section is also capable of floating when detached from the other section of the boat and is provided with a suitable ballast 8 to prevent the same from rolling unnecessarily. 100

The section 3 has an opening 9 at the top which is provided with a cover 10 pivotally mounted thereon and adapted to be securely fastened by fastening means 11 to prevent water from splashing into the interior of 105 said section. The cover 10 also has supported thereon an upwardly extending ventilating device 12 comprising a series of shutters

13 arranged preferably in the rear wall thereof through which air may be taken from the atmosphere above the surface of the water, and these shutters are adapted to 5 be opened and closed from the interior of the section so that when the sea is very rough the waves will be prevented from splashing into the same.

A periscope 14 is also preferably mounted 10 on the cover 10 so that the operator thereof may be able to properly guide the boat. The two sections 1 and 2 of the boat are cut away at 15 and 16 respectively to provide space whereby the cover 10 may be opened 15 or closed by the operator of the boat so as to provide access to the interior.

The forward section 1 and the stern section 2 are provided with hatches 17 and 18 respectively in the decks thereof, through 20 which access may be had to the interiors of these sections, these being the only openings for said sections. The forward section of said boat is preferably provided with a torpedo tube 19 capable of holding, in the 25 present instance, one torpedo 20, said tube having an opening 21 at the forward end thereof through a bulkhead 22 formed in the bow of the boat for the purpose of preventing water from entering the main portion of said boat.

The tube 19 has communication, through said opening 21, with a small compartment 23 formed in the bow of said boat, and this compartment, in turn, has openings 24 through which the torpedo may be ejected 35 into the water. Under normal sailing conditions, it is desirable to keep the openings 24 closed so that the chamber 23 and the interior of the torpedo tube will not provide 40 too much resistance to the progress of the boat, and for this purpose doors 25 and 26 are pivotally secured to the side of the boat by hinges 27 which have longitudinally disposed axes, and these doors may be normally held closed by suitable means such, 45 for instance, as springs 28 and 29 respectively.

Guards 30, 30 are formed on said doors to be engaged by the torpedo which is being 50 discharged, and these guards assist in forcing said doors open sufficiently wide to prevent the interference with the movements of said torpedo. The stern section preferably contains the propelling instrumentalities 55 which include, in the present instance, an engine 31 and fuel tank 32, said engine being provided with a shaft 33 which extends to the stern of the boat where it has attached thereto a propeller 34.

A fin 35 extends upwardly from the deck 60 of the stern section of the boat to a point normally above the water line and provides a shield for a pipe 36 through which air is drawn to the carburetor of the engine. The 65 operations of the engine 31 are controlled

from the operating section 3, preferably by a suitable means extending through the bulkhead 6 and the wall of the section 3, said means including a shaft 37.

This shaft is arranged within a sleeve 38 70 which also projects through the bulkhead 6 and the wall of the section 3 and has upon the inner end thereof a wheel 39 constituting the steering wheel for the boat. The shaft 37 and the sleeve 38 are each formed in 75 two sections 37', 37² and 38', 38² respectively and these sections are joined together by couplings 40 and 41 respectively which are interposed preferably between the bulkhead 6 and the section 3 and are adapted to 80 automatically disconnect when the section 3 is separated from the forward and stern sections of the boat.

The sleeve 38 is operatively connected with a rudder 42 arranged at the stern of 85 the boat, by means of a shaft 43, sprockets 44 and 45 and chain 46. The torpedo 20 is, in the present embodiment, adapted to be ejected from the torpedo tube 19 by compressed air which is preferably supplied, 90 through a tube 47, from a tank 48 arranged within the stern section 2.

The tube 47 passes through the compartment 7 beneath the section 3 and in order to permit the sections 1 and 2 to be separated 95 when required, it is necessary that a coupling be inserted in the pipe 47. This coupling preferably embodies in its construction a valve casing 49 containing a valve 50 operated from the interior of the section 3. 100

The two sections of the tube 47 are inserted in opposite ends of the casing 49 and these sections are adapted to be readily disconnected when anything happens to the two sections of the boat which would require the 105 separation thereof. The sections 1 and 2 of said boat are preferably detachably connected together by two sets of hooks 51 and 52.

The hooks 51 are secured to opposite ends 110 of a shaft 53 arranged within the section 3 and transversely thereof, said hooks being arranged to engage projections 54 attached to the forward section 1 of said boat. The shaft 53 has a lever 55 secured thereto with 115 in the section 3 and by which the operator may rock said shaft 53 when it is desired to connect or disconnect the section 3 from the section 1.

The hooks 52 are secured to opposite ends 120 of a shaft 56 which is likewise journaled to rock transversely of the section 3, and this shaft also has attached to it an operating lever 57 to enable the operator to more easily rock the shaft when it becomes necessary to disengage the hooks 52 from projections 58 on the stern section 2 of the boat in order to disconnect said operator's section from said stern section.

From the above specific description, it 130

will be seen that the operator of the boat will be amply protected in his operating section and in case the forward and stern sections are destroyed or injured so as to retard the progress of the boat, either one or both of said sections may be disconnected from the operator's section. If the forward section is released, the stern section may still supply power to propel the operating section to a place of safety, or if both forward and stern sections are destroyed the operating section may be disconnected from both and remain afloat until rescued.

Having thus specifically described my invention what I claim and desire by Letters Patent to secure is:

1. A boat comprising a forward section, a stern section, an operating section constructed and arranged to be inclosed by said forward and stern sections, and means for detachably securing said sections together.

2. A boat comprising a forward section, a stern section, an operating section constructed and arranged to be inclosed by said forward and stern sections, and means operable from within said operating section adapted to secure said sections together.

3. A boat comprising a forward section, a stern section, an operating section adapted to be one half inclosed by said forward section and one half by said stern section, and means operable from within said operating section adapted to secure said forward and stern sections to said operating section.

4. A boat comprising a plurality of independent sections, one of said sections constituting an operating compartment and being inclosed by said other sections, and means operable from within said operating

compartment constructed and arranged to 40 detachably secure said plurality of sections together.

5. A boat comprising a forward section, a stern section detachably connected with said forward section, and a spherical casing 45 arranged one half in said forward section and one half in said stern section, said spherical casing constituting an operating compartment.

6. A boat having, in combination, a forward section and a stern section arranged end to end, a bulk head for the adjoining ends of each of said sections, an operating section arranged between the bulk heads of said forward and stern sections but inclosed 55 thereby and independent of said sections, and means for detachably securing said several sections together.

7. A boat having, in combination, a forward section, a torpedo tube arranged in 60 said forward section, a stern section detachably connected with said forward section, steering means for said boat, propelling means therefor, means for discharging a torpedo from said tube, an operating section 65 inclosed between said forward and stern sections, and operating instrumentalities arranged within said operating section and extending therefrom to said steering means, said propelling means and said torpedo discharging means.

In testimony whereof I have hereunto set my hand in presence of two subscribing witnesses.

WILLIAM O. CUTTER.
